UNITED STATES PATENT OFFICE.

SAMUEL S. SAMPLINER, OF CLEVELAND, OHIO, ASSIGNOR TO THE RICH-SAMPLINER
KNITTING MILLS COMPANY, OF CLEVELAND, OHIO, A CORPORATION OF OHIO.

DESIGN FOR A KNITTED CAP.

Application filed November 29, 1926. Serial No. 19,865. Term of patent 14 years.

To all whom it may concern:

Be it known that SAMUEL S. SAMPLINER, a citizen of the United States of America, residing at Cleveland, in the county of Cuyahoga and State of Ohio, has invented a new, original, and ornamental Design for Knitted Cap, of which the following is a specification, reference being had to the accompanying drawing, forming a part thereof.

Fig. 2, is a view thereof in rear perspective.

The design is characterized by an upturned outer head band for the cap comprising zigzag sections or areas terminating in an upper serrated edge.

I claim:

The ornamental design for a knitted cap, as shown and described.

In testimony whereof I do now affix my signature.

SAMUEL S. SAMPLINER.
